[57] CLAIM

The ornamental design for a surgical incision spreading device, as shown and described.

DESCRIPTION

FIG. 1 is a top perspective view of a surgical incision spreading device of the invention in a first deployment configuration;

FIG. 2 is a top elevational view of the surgical incision spreading device of FIG. 1;

FIG. 3 is a bottom elevational view of the surgical incision spreading device of FIG. 1;

FIG. 4 is a right elevational view of the surgical incision spreading device of FIG. 1, the left elevational view being the same;

FIG. 5 is a front elevational view of the surgical incision spreading device of FIG. 1, the rear elevational view being the same;

FIG. 6 is top perspective view of the surgical incision spreading device of FIG. 1, but illustrating the surgical incision spreading device in a second deployment configuration;

FIG. 7 is a top elevational view of the surgical incision spreading device of FIG. 6

FIG. 8 is a bottom elevational view of the surgical incision spreading device of FIG. 6;

FIG. 9 is a right elevational view of the surgical incision spreading device of FIG. 6, the left elevational view being the same; and,

FIG. 10 is a front elevational view of the surgical incision spreading device of FIG. 6, the rear elevational view being the same.
